UNITED STATES PATENT OFFICE.

DAVID DECKER, OF NEW YORK, N. Y.

IMPROVEMENT IN PIANO-FORTES.

Specification forming part of Letters Patent No. 38,731, dated June 2, 1863.

To all whom it may concern:

Be it known that I, DAVID DECKER, of the city, county, and State of New York, have invented a new and useful Improvement in Piano-Fortes; and I do hereby declare that the following is a full, clear, and exact description of the same, reference being had to the accompanying drawings, forming part of this specification, in which—

Figure 1 is a plan view of the stringed portion of a square piano-forte constructed according to my invention. Fig. 2 is a longitudinal vertical section of the same. Fig. 3 is a transverse vertical section of the same.

Similar letters of reference indicate corresponding parts in the several figures.

This invention consists in an improved construction of what is termed, in piano-fortes, the "full metallic plate," whereby I avoid bringing any of the string-bearings on such plate, and am enabled to bring the connections of the strings with the tuning-pins close to the wrest-plank, and so prevent the leverage and great strain on the pins, which is unavoidable when the strings pass over the plate, as has commonly been the case when the plate has been used. By these means I obviate the only objections heretofore existing to the use of such plate, which is so advantageous in all other respects.

To enable others skilled in the art to make and apply my invention, I will proceed to describe it with reference to the drawings.

A B C D indicate the several portions of the full metallic plate. The portion A of the said plate, adjacent to the sound-board bridges *a b c*, is of well-known form, and the back portion, B, which is secured by screws *g g* to the wrest-plank F, is, as in some instruments heretofore constructed, only of such width from back to front as not to reach so far forward as the tuning-pins *d d*; but the portion C, which connects the portion B with the front brace, D, at the left-hand end of the instrument, is so much elevated between B and D as to pass entirely over the longer or bass strings *e e*, thus enabling a wooden bridge, *f*, to be used upon the wrest-plank to form the necessary support for these strings near their tuning-pins, the said bridge *f* being partly situ-

ated under the said elevated portion C of the plate, as shown in Figs. 2 and 3, and indicated in dotted outline in Fig. 1. The said portion C connects with the front brace, D, in the usual manner, and is secured in front of the said brace by screws *h h* to the blocking G at the left-hand end of the instrument. By this construction of the plate it will be understood that all the strings of the instrument are enabled to be supported entirely upon wooden bearings, which is very desirable to produce a good and even tone, and they are also enabled to be brought close to the wrest-plank, which is impossible when the plate fits close to the plank and extends beyond the tuning-pins, as the holes provided in the plate for the pins in that case have to be large enough for the pins to pass through without touching the metal, and the strings are necessarily attached to the pins at a distance from the bearing of the latter in the plank equal to the thickness of the plate. By bringing the strings close to the plank the great strain on the pins, consequent upon having them at a distance above, is avoided, and the instrument keeps longer in tune and is rendered altogether more durable. To provide for the tuning of those strings which pass under the said elevated portion C of the plate, there are made in the said portion of the plate, opposite to the tuning-pins *d d* of the strings, holes *i i*, large enough to permit the application of a tuning-key to the heads of the said pins.

What I claim as my invention, and desire to secure by Letters Patent, is—

Elevating the portion C of the plate in such manner that it passes entirely over a number of the longer or bass strings *e e* of the instrument, and enables the said strings to pass between it and the wrest-plank, and so enables a wooden bridge, *f*, to be used upon the wrest plank for the support of those strings, and the said strings to be brought close to the wrest-plank, substantially as and for the purpose herein specified.

DAVID DECKER.
